UNITED STATES PATENT OFFICE.

CHARLES J. EVERICKX, OF PARIS, FRANCE.

IMPROVEMENT IN FOLDING CHAIRS, TABLES, &c.

Specification forming part of Letters Patent No. 222,883, dated December 23, 1879; application filed June 30, 1879.

To all whom it may concern:

Be it known that I, CHARLES JOSEPH EVERICKX, of Paris, in the Republic of France, have invented a new and Improved Folding Table or Chair, of which the following is a specification.

The object of the invention is to provide a system of articulation or joints for portable furniture, so that the same can readily be folded up to occupy a very small space and can be conveniently carried.

The invention consists in the arrangement of a cross-bar of a chair or table, and of the legs and top, so that the legs are pivoted at the end of the cross-bar, and can be folded, so that the chair, table, or like piece of furniture can be easily carried by means of a handle or strap that is fastened to the cross-bar, and suspended from this cross-bar may be a valise or satchel.

In the drawings, Figure 1 shows a front elevation of a folded chair with my invention applied. Fig. 2 is a side elevation of the same. Fig. 3 is a perspective view of the same set up for use. Figs. 4, 5, and 6 are details, showing the precise construction of the joint. Fig. 7 is a perspective view of a table to which my invention is applied.

Similar letters of reference indicate corresponding parts.

In Figs. 4, 5, and 6, *c* and *d* are two plates of metal, in which the legs *a' b' a b* are pivoted by means of small bolts or pins *r' r* and *r*, each pair of legs *a b* and *a' b'* being similarly constructed and jointed to the plates *c d*. Fastened to the leg *a'*, and lying between *a'* and *b'*, is a small metal plate, *f*, provided with an inclined flange, *m*. The top of the leg *a'* is beveled, as is shown at *t* in Fig. 4.

O is a metal partition, which separates the joint of the leg *a' b'* from the joint of *a b*. When the chair or table is folded up the two legs *a' b'* lie parallel to each other—*a'* to the outside, *b'* to the inside—as in Figs. 1 and 5.

When the chair or table is set up for use the legs are turned on the pin *r* or *r'*, so as to be inclined toward each other, as shown in Fig. 3. The inclination of the legs *a'* and *b'* to each other is fixed in the following manner: The leg *a'* can be inclined until the surface of

the bevel *t* lies up close to the partition *O*, as shown on the right-hand side of Fig. 4. It cannot be inclined any more, as the partition *O* would interfere. As there is a leg on each side of the partition *O*, the same will receive no strain, and the legs will press against the opposite sides with equal pressure.

The metal plate *f'*, with the inclined flange *m*, fixes the inclination of *b*, for if the leg *a* is inclined, as shown in the right side of Fig. 4, the leg *b* can be inclined until it lies close up to the flange *m*. If the leg *b* were to be inclined farther, it would cause a greater inclination of *a*, as *f* and *m* are secured to *a*; but this is prevented by the partition *O*.

If my invention is applied to a folding chair, it will be arranged in the following manner: Figs. 1, 2, 3 show the chair folded for transportation. *a' b'* form one set of legs, and *a b* the other set. They are connected as has been described. The metal plates *c* and *d*, which constitute the bearing for the whole joint, are fastened to a cross-bar, *p*. This cross-bar is provided with a handle or strap, *l*, by means of which the folded chair can be carried. Suspended from this cross-bar *p* is a satchel, valise, &c. The thickness of this valise or satchel is equal to the width of the two legs *a' a*, as is shown in Fig. 2.

a'' a'' are cross-bars connecting the legs *a'* and *a' a*. *b''* is a cross-bar connecting the two legs *b' b'*. *n n* are notches in the cross-bar *p*, into which the legs *b' b' b' b'* fit when the chair is set up. *g g* is the seat of the chair, and may be either of oil-cloth, canvas, cane, wood, or other suitable material.

To the under side of the frame of the seat are fastened the jaws *x x*, between which the other ends of the legs *b' b'* are pivoted. The legs *b' b'* are provided with notches at their ends, and fit into recesses on the under side of the frame of the seat.

If the chair is folded as is shown in Figs. 1 and 2, and it is desired to set up the same, the operation will be as follows: The seat *g* is first drawn out, as is indicated by the arrow 1, Fig. 2. The legs *b' b'* are then drawn out, as indicated by the arrow 2. They can be inclined or turned until the leg *b* presses against the flange *m*, Fig. 4, and will then draw the leg *a* out in the direction of the arrow 3. These

legs can only be inclined until the bevel *t* touches the partition *O*. The legs *a'* and *b'* are drawn out in the same manner, the seat is secured to the ends of *b'* and *b*', and the chair is ready for use.

By reversing these motions the chair can be very easily folded.

The invention can be applied to a table in the same manner as is shown in Fig. 7. The ends of the legs *b b*' are here shown as provided with small hooks or flanges, which fit in the hollow of metal plates which are fastened to the under side of the table.

I have shown the table as being constructed of bamboo cane, but do not limit myself to this material, for the chairs or tables may be constructed of any kind of material used in the construction of furniture.

This peculiar construction of the joint can be applied to any-sized table, chair, &c., and may be used with or without a satchel or drawer attached to the cross-bar *p*.

Having thus described my invention, I claim as new and desire to secure by Letters Patent—

1. A joint for portable chairs or tables, consisting of the metal plates *c* and *d*, connected by the metal partition *O*, and of the pins *r* and *r'*, as and for the purpose set forth.
2. The combination of the partition *O*, lower leg, *a'*, provided with a bevel, *t*, and strip *f*, having a flange, *m*, and of the upper leg, *b'*, both being pivoted on the pin *r'*, as and for the purpose set forth.
3. The combination of the cross-bar *p*, of joint-plates *c* and *d*, and of the legs *a' b' a b*, as and for the purpose set forth.

C. J. EVERICKX.
